A. E. ROGERS

NURSING NIPPLE

Original Filed March 14, 1923

Inventor

Almaeun E. Rogers.

UNITED STATES PATENT OFFICE.

ALMERIN E. ROGERS, OF PLACENTIA, CALIFORNIA.

NURSING NIPPLE.

Application filed March 14, 1923, Serial No. 625,039. Renewed November 10, 1926.

This invention relates to improvements in nursing nipples.

The prime object of my invention is to provide a nursing nipple with interior screw threads so that the nipple may be secured on the mouth of a bottle against accidental dislodgment.

A further object of my invention is to provide a nursing nipple formed of a single piece of rubber, but having the enlarged end of the nipple with the screw threads formed of hard rubber compound, while the small end of the nipple is formed of a soft flexible rubber compound.

A still further object of my invention is to provide a nipple of the above indicated character that will securely engage the mouth of a bottle and prevent any of the contents of the bottle from leaking out between the threads and the bottle.

An additional object of my invention is to provide a nipple of the above indicated character, which is simple in construction, efficient for the purpose intended, and one that can be manufactured at a relatively low cost.

These and like objects of the invention will be better understood as the description proceeds and as is specifically pointed out in the appended claims.

Referring to the accompanying drawing which forms a part of this specification and which better illustrates the construction of my improved nipple,

Figure 1 is a side elevation of a nursing bottle having my invention applied thereto.

Figure 2 is a vertical section of my improved nipple, and

Figure 3 is an end view of same.

Referring to the accompanying drawings in detail, like characters will be used to designate like parts in the different views.

In the drawing, the numeral 1 indicates a nursing bottle having graduations stamped on one side of same.

Heretofore, most nursing bottles have been provided with a lip adjacent the mouth of the bottle, and it has been necessary to pull the enlarged end of the nipple over the lip when placing same on the bottle. This has proved to be very difficult when first using

the nipple, and after the nipple has been used a number of times, it stretches and will not firmly hold in engagement with the mouth of the bottle.

55

In order to eliminate the above described undesirable features of the present day nipple, I have constructed a nipple that while formed from a single piece of rubber, is composed of two different kinds. The numeral 3 designates the body of the nipple which is formed with a reduced end 4 having an aperture 5 therethrough, through which communication may be had with the contents of the bottle 1 when the nipple is in position. 60 The enlarged end of the nipple as at 6 is formed of hard rubber and is provided on the interior of same with threads 7 for engagement with threads formed on the mouth of the bottle. A shoulder 8 is formed in the 65 enlarged portion 6 which provides a seat for the packing ring 9.

From the foregoing description of my invention, it can be readily seen that I have provided a nipple which eliminates all of 70 the undesirable features of the present type of nipple and at the same time embodies the desirable features, as above stated.

In view of the foregoing description of my invention taken in connection with the 75 accompanying drawing, it is thought that any further explanation as to the construction of same is unnecessary.

While I have shown and described the preferred form of my improved nipple, I 80 wish it to be understood that various minor changes may be resorted to as will fall within the spirit and scope of the claims appended.

What I claim as new and desire to secure 85 by Letters Patent is:

1. A nursing nipple formed in one piece having soft flexible rubber at one end and hard rubber on the opposite end to provide screw threads.

95

2. In a nursing nipple, formed in a single piece, a soft rubber compound forming the reduced end of said nipple, and a hard rubber compound forming the enlarged end of said nipple to provide interior screw threads for 100 engagement with the threads on the neck of a bottle.

3. In a nursing nipple, formed in a single piece, a soft rubber compound forming the reduced end of said nipple, a hard rubber compound forming the enlarged end of said nipple to provide interior threads for engagement with threads on the neck of a bottle, a shoulder formed in the hard rubber

compound, and a soft rubber washer to be received between the shoulder and the top of the bottle.

10

In testimony whereof, I have affixed my signature.

ALMERIN E. ROGERS.
